(57) **CLAIM**

The ornamental design for a flush toilet shroud, as shown and described.

DESCRIPTION

FIG. 1 is a front and side perspective of a flush toilet shroud showing our new design;

FIG. 2 is a front elevation view thereof;

FIG. 3 is a right side elevation view thereof;

FIG. 4 is a left side elevation view thereof; and,

FIG. 5 is a top plan view thereof.

The broken line showing of portions of the flush toilet is for illustrative purposes only and forms no part of the claimed design.
